SNOW BLOWER FAN FOR SNOW REMOVAL EQUIPMENT

Lloyd C. Hahn, Vanderburgh County, Ind., assignor to
Hahn Inc., Evansville, Ind., a corporation of Indiana

Filed June 13, 1966, Ser. No. 2,656

Term of patent 14 years

(Cl. D35—2)

FIG. 1

FIG. 3

FIG. 2

FIG. 1 is a perspective view of a snow blower fan for snow removal equipment, showing my new design;

FIG. 2 is a front elevational view thereof; and,

FIG. 3 is a side elevational view thereof, looking from right to left in FIG. 2.

I claim:

The ornamental design for snow blower fan for snow removal equipment, as shown.
